JAMES W. HIGHLEYMAN, OF POCATELLO, IDAHO, ASSIGNOR OF ONE-HALF TO JAMES G. BLUNT, OF SCHENECTADY, NEW YORK

CROSS HEAD GUIDE FOR ENGINES

Application filed September 10, 1928. Serial No. 304,899.

This invention pertains to cross head guides intended primarily for use in locomotive engines, though capable of use in engines of other types.

5 The invention consists in a novel expansion joint for connecting the guide bars at one end to a guide yoke or bracket of usual form, and at the other end to the bolting flanges carried by the cylinder head, in the case of locomotives. In other types of engine the usual supports provided for the guide bars will be employed instead of the guide yoke or bracket and bolting flanges above referred to.

15 The purpose of the expansion joint is to compensate for expansion and contraction of the guide bars, or of other parts with which they may be connected, and thus to prevent transfer of stresses from the guide bars to their supports, or from such supports to the 20 guide bars.

The invention is illustrated in the accompanying drawing, in which:

Fig. 1 is a side elevation of my improved cross head guide showing the cross head and the proximate end of the cylinder and steam chest;

Fig. 2 is a side elevation of the upper guide bar, broken away at its midlength and sectioned at its ends to show details of construction;

Fig. 3 is a bottom face view of the upper guide bar;

Fig. 4 is a cross section of said upper guide bar;

Fig. 5 is a fractional side elevation of the cylinder end of the upper guide bar showing the seat or cavity provided for the sliding plate through which the fastening bolts pass;

Fig. 6 is a lower face view of the sliding plate employed at the guide yoke end of the upper guide bar;

Fig. 7 is a plan view of the sliding plate used at the cylinder end of the guide bar.

It is to be understood that the sliding plate 45 construction may be used at either or at both

ends of the guide bar, and if desired, of both guide bars.

In the drawing the numeral 1 designates the engine cylinder, 2 the cylinder head, 3 the bolting flanges projecting from the cylinder head, 4 the upper bar of the cross head guide, 5 the lower bar thereof, and 6 the guide yoke or bracket made fast to the engine boiler and serving as the outer end support for the bars 4 and 5. These guide bars 4 and 5 may be of usual construction except for recesses or cavities 7 and 8 formed in one or both ends of the upper bar 4 or of both bars 4 and 5, to receive sliding plates 9 and 10, hereinafter more fully described. Passing vertically through the guide bar 4 and symmetrically arranged within recess or cavity 7 are elongated holes or openings 11 to permit passage of bolts 12 (Fig. 1), the width of the openings 11 being equal to the diameter of the bolts 12, and the length of said openings being somewhat greater than such diameter, to permit limited play of the bolts therein. Similarly, the cylinder end of guide bar 4 is provided with elongated openings 13 to permit the passage through them of bolts 14. the location of the openings 13 within the recess or cavity 8 and the relative dimensions of bolts 14, being the same as at the opposite end of the guide bar.

75 Referring to Figs. 2 and 6, the plate 9 is shown of a width and thickness to fit somewhat snugly at its sides or edges within the cavity 7 of guide bar 4, but of shorter length than said cavity, to permit a limited longitudinal movement or play of said plate 9 within said cavity. This plate 9 is provided with bolt holes 15 of a diameter sufficient to receive but to closely fit, the fastening bolts 12 which pass through them, and said holes 80 are countersunk on the lower face of plate 9 to receive the heads of said bolts.

The bolt holes 15 are so positioned that their centers will register with the centers of the openings 11 of guide bar 4 when the ends 85

of the sliding plate 9 are equally spaced from the ends of the cavity 7, so that in the event of expansion or contraction causing longitudinal movement of the guide bar 4 relatively to the guide bar 5, there shall be clearance for the bolts 12 sufficient to compensate for such movement in either direction.

The same construction and relation of parts obtains as to recess or cavity 8 and plate 10 except that said cavity is in the upper side or face of guide bar 4 and shorter than cavity 7, and is here shown as provided with two elongated holes 13 instead of four. Furthermore, the bolt holes 16 of plate 10 are not shown countersunk, but may be countersunk if this be deemed desirable. However, owing to the relatively short plate illustrated it is preferred to omit the countersinks, and secure the additional strength incident to the thicker metal afforded.

The parts being constructed as above set forth, are assembled as shown in Fig. 1, the cylinder ends of bars 4 and 5 being secured to the bolting flanges 3 of the cylinder head by the bolts 14 which pass radially outward through the flanges 3, nuts being applied to the outer ends of said bolts. Similarly, the bolts 12 are passed outward through the bars 4 and 5 and bracket 6, this being desirable in the case of the bracket ends because of the passage of the cross head 17 over the heads of the bolts, whereas the nuts would, if the bolts were reversed, interfere with such passage.

As above mentioned this construction may be applied to both the upper and the lower bars 4 and 5, though here shown as applied to the upper one only. As this is a matter of duplication it is not deemed necessary to illustrate the same.

Except as herein set forth the structure may follow common practice in the locomotive or engine art.

In assembling the parts the plates 9 and 10 are positioned in their respective seats 7 and 8, and bolts 12 and 14 are passed radially outward through the respective openings, and equipped with retaining nuts as shown in Fig. 1. Jam nuts may be added if deemed necessary. The bolts 12 and 14 fitting closely within the openings 15 and 16 of plates 9 and 10, and being drawn home by the nuts, produce friction between the bottoms of the seats or cavities 7 and 8 and the contacting faces of said plates 9 and 10, proportionate to the adjustment of the nuts. This adjustment will be such as to maintain the parts in relatively fixed position so long as no appreciable or material stress is set up through expansion or contraction tending to move the guide bars 4 and 5 or their supports relatively to one another, but not sufficient to hold said bars against relative movement in the event that a dangerous stress incident to expansion or contraction occur,—such a stress

as would be likely to strain or distort the guide bars or their supports if not relieved.

By the employment of the plates 9 and 10 and the provision for longitudinal movement thereof relatively to the guide bars, or vice versa, contact surfaces of considerable area are provided, and the friction incident to the tightening of the bolts is distributed over such considerable area. Consequently, there will be at no point pressure sufficient to embed the contacting faces one in the other. In this way adequate friction is afforded to ensure retention of the parts in proper relative position yet permit automatic adjustment thereof to compensate for any material expansion or contraction.

In some cases cross head guides employ a single guide bar, the cross head being formed with an opening or with flanges to receive or to engage the guide bar and prevent accidental disengagement therefrom. It is to be understood that the present invention is applicable to cross head guides of this type as well as to the two bar type here illustrated.

I claim:

1. An expansion joint for a cross head guide, comprising fixed end supports therefor; a guide bar having a recess in its bearing face and elongated holes passing through said bar within the bounds of said recess; a plate provided with bolt holes perpendicular to its face and spaced to axially align with the holes in the guide bar, said plate being shorter than the recess in said bar; and bolts seated in the bolt holes of the plate, passing through said plate, through the elongated openings in the bar, and secured in holes formed in the support, said bolts serving to maintain the plate in fixed position and to hold the plate and bar in close frictional contact, but to permit longitudinal movement of the bar relative to the plate to compensate for expansion and contraction of the bar.

2. In combination with a cross head guide bar and a support therefor, an expansion joint comprising a plate seated in a recess in a face of said bar and provided with countersunk bolt holes in its outer face; bolts passing through said holes and having their heads seated in the countersinks in said holes and their stems passing through elongated openings in the guide bar; and fastenings applied to the threaded ends of the bolts and serving to produce a variable friction between the contacting faces of the guide bar and the plate.

3. An expansion joint for cross head guides comprising a guide bar provided with openings elongated in the direction of the length of said bar; a plate placed in face contact with the portion of the bar containing said elongated openings and provided with bolt holes spaced to register axially with the elongated openings of the bar when the plate is positioned symmetrically with reference to

said openings; a support for said bar; and bolts passing through said support and through the openings in the bar and the bolt holes of the plate, and serving to draw together and hold said parts with friction sufficient to maintain them normally in fixed relation but to permit relative movement of the bar and plate under forces incident to expansion or contraction acting upon said joint.

In testimony whereof I have signed my name to this specification.

JAMES W. HIGHLEYMAN.
